UNITED STATES PATENT OFFICE.

JOHN A. LAMONT, OF CHICAGO, ILLINOIS, ASSIGNOR TO AMERICAN STEEL FOUNDRIES,
OF CHICAGO, ILLINOIS, A CORPORATION OF NEW JERSEY.

RAILWAY CAR.

Application filed July 10, 1922. Serial No. 573,991.

To all whom it may concern:

Be it known that I, JOHN A. LAMONT, a citizen of the United States, residing at Chicago, in the county of Cook and State of Illinois, have invented certain new and useful Improvements in Railway Cars, of which the following is a specification.

This invention relates to railway cars and more particularly to a bolster shock absorber 10 arrangement.

In cars of the type and capacity requiring six wheels the side roll or rocking of the car body on the trucks is unusually severe under load, due primarily to a relatively high center of gravity. This rocking reaches a maximum at a certain fixed speed and evidently is due to a synchronized condition between the wheels striking the rail joints and the natural oscillation of the 15 springs under the heavy load. The blow or pounding action delivered on the side bearings by the rocking motion results in great damage to equipment generally and a marked tendency to take the load from the 20 wheels on the opposite side of the truck to which the blow is concentrated. This tendency is unusually great in cases where the 25 side bearings are high relative to the center plate, and especially so where such side bearings are relatively a great distance outwardly from the center plates.

It has been standard practice on center bearing trucks to allow a limited clearance between the car body side bearings and the 35 truck bolster side bearings, either of the friction or roller type, in order to insure a concentration of the load on the center plate, thus providing for free swiveling of the truck on curves and also relieving the car 40 body of some of the weaving or twisting due to minor imperfections of the road bed. The side bearing clearance referred to aggravates the tendency of the car body to rock. This rocking takes place between the 45 center plates but the pivot or fulcrum point of this rocking force is at the side bearings and consequently the latter are required to absorb the resultant shock.

Accordingly, one object of my present invention is to reduce the side rolling or rocking of railway cars, particularly heavy capacity cars using six wheel trucks, although the invention is applicable to lighter capacity cars using four wheel trucks.

Another object of the invention is to pro-

vide a novel bolster and side bearing arrangement adapted to reduce side rolling or rocking and further adapted to meet all of the requirements under service conditions.

These and other objects are accomplished 60 by means of the arrangement shown on the accompanying sheets of drawings, in which—

Figure 1 is a fragmentary end elevation of a railway car showing parts of the bolster 65 mechanism in section and embodying my invention;

Figure 2 is a fragmentary top plan view of the three-piece bolster arrangement embodying the invention;

Figure 3 is a side elevation of the bolster, parts being shown in section to show the means for absorbing rocking actions; and

Figure 4 is a detail perspective view of a member secured to the longitudinal bolster 75 members for assisting in retaining the shock absorbing means in position.

The various novel features of the invention will be apparent from the following description and drawings, and will be particularly pointed out in the appended 80 claims.

Referring to the figures of the drawings, it will be noted that I have illustrated the invention in connection with a railway car 85 having a main body portion 10 in which material such as coal and the like, is carried, said body having side bearings 11 which engage side bearings 12 secured to or formed on longitudinally extending 90 bolster members 13. I prefer to provide no clearance between the side bearings 11 and 12, for, as mentioned hereinabove, in cases where such side bearings are located at a point relatively high above the center plates 95 14, side rolling is excessive when such clearance is allowed at such points, and that the rolling and pounding action becomes excessive when such clearance is provided under the conditions stated. The under frame of 100 the car body 10 includes a center sill structure 15 to which is connected the upper center plate 14 which rests and pivots upon the under center plate 14 carried by the main transverse bolster member 16 which, 105 in this instance, is formed integrally with the longitudinal bolster members 13. The longitudinal bolster members 13 at their ends are connected by cross pieces 17 which are integrally formed therewith, such cross 110

pieces having lower convex rocker surfaces 18 which rest and are adapted to rock on the relatively flat surfaces 19 of the intermediate portions of transversely extending 5 bolster members 20 for equalizing purposes. The bolster unit comprising the bolster members 16, 13 and 17 may be called the equalizing bolster member. It will be understood that the bearing portions 21 of the 10 cross bolster members 20 rest upon suitable bearing portions of the truck side frames, or associated parts not shown. These bolster bearing portions 21 may be curved whereby same may have a relative rocking 15 movement on the associated bearing members such as equalizing levers or side frames for permitting relative vertical angularity of movement such as occasioned in operating over vertical curves or curves resulting from change in vertical inclination of 20 the tracks.

With the truck standing on a level track the center plate load is carried by the double girder or center plate portion 14 to the 25 side girders 13 which, in turn, deliver their loads to the end girders 17.

Referring particularly to Figure 1 of the drawings, it will be noted that the middle 30 portions of the end girders 17 bear upon the middle portion of the cross bolster members 20 and that the ends of the end girder members 17 have bearing portions 22 which are slightly spaced from bearing portions 23 on the cross bolster members 20 when the 35 equalizing bolster member is in its normal middle position. In this connection it will be appreciated that the vertical distance between the bearing portions of the end girders and the bearing members 23 at the ends 40 of the end girders is slightly greater than the downward set of intermediate portions of the cross bolster members. By providing the slight vertical distance between the bearing portions 22 and 23 of the end girder members 17 and cross bolster members 20, a clearance is obtained which insures a 45 center bearing at all times and thus provides for an equal distribution of the loads to the ends of the cross bolster members 20 when 50 a truck is riding practically level. Each of the cross bolster members is provided with side stops 24 which limit relative lateral movement between the equalizing bolster unit and the cross bolster members 20. 55 The bolster construction described, in a large measure, overcomes the tendency of a car body to rock or roll due to unevenness of the road bed, in that the limited clearance provided between the side bearings 22 and 23 permits a proportionately 60 large upward and downward movement of the opposite end of the cross bolster bearing without disturbing the equilibrium of the load on the center plate. For example, 65 referring to Figure 2 of the drawings, if

the right hand end of the farther cross bolster member 20 dips to take care of a depression in the track at that corner of the truck the equalizing bolster unit in effect 70 rolls away from the center toward the opposite end of the cross bolster member until the side bearings 22 and 23 at that end come in contact. If at the same time the left hand end of the nearer cross bolster member 20 dips, the equalizing bolster unit in 75 effect rolls on said bolster member toward its opposite end until the opposite bearings are in engagement with each other. Under such conditions the diagonally arranged 80 side bearings are in engagement with each other for stabilizing the load and limiting the rolling action to a minimum amount. Of course, it will be understood that the equalizing bolster unit does not roll simultaneously in opposite directions on the cross 85 bolster members 20, but it does so in a relative manner. As a matter of fact, it is the opposite ends of the cross bolster members 20 which rise or fall and the equalizing bolster unit remains horizontal. 90

However, in the combination which is shown in the drawings, the side bearing members 22 and 23 normally do not pass into engagement with each other under rolling or rocking conditions, but, on the other hand, 95 I have provided means interposed between the equalizing bolster unit and the transverse bolster members 20 for absorbing the rocking or rolling action and more particularly for absorbing the pounding or shocks incident thereto, which is so pronounced in the ordinary side bearing structures in which the body side bearings have a clearance with respect to and engage side bearings on the bolsters. The shock absorbing medium preferably is located at the four corners of the 100 equalizing bolster unit to act as a check on this rocking movement of the car body on the truck which would naturally take place between the equalizing bolster unit and the 105 cross bolster members 20. The resistance of this shock absorber will be in direct proportion to the rocking movement between the equalizing bolster unit and the cross bolster members 20 and will act as an effective retarding or snubbing force. 110

As a shock absorbing means I choose to use a number of thin metal plates 25 piled one on top of the other and working as a unit and so arranged that the bending and 115 also frictional resistance will act as a counter force to the rocking movement. These thin plates 25 preferably are of steel and are mounted in pockets 26 formed at the four corners of the equalizing bolster unit. 120

As shown particularly in Figures 3 and 4 of the drawings, a casting 27 is shown as inserted in the upper portion of each of the pockets 26, said casting in each case having 125 a wall 28 for closing the opened side of the 130

6 pocket 26 and for holding the thin frictional metal plates 25 in position, it being understood that the casting 27 in each instance is secured in place by any suitable means, such as rivets 29. To assist in locating the casting the latter is provided with a projection 30 which extends through a small opening in the upper outer portion of each pocket 26. It will be understood that the thin metal 10 plates 25 are placed in the pockets 26 before the supporting castings 27 are set and secured in place, it being noted particularly in Figure 3 that each pile of plates is supported on ledges 31 forming parts of the 15 equalizing bolster unit.

Particular attention is called to the fact that the under-surfaces 32 of the upper part of each casting 27 is concave for permitting the metal plates 25 to bow upwardly when 20 the lower metal plate and side bearing 33 pass into engagement with each other, due to a rolling or rocking action of the car. Preferably the top of each convex bearing 33 will have the same radius of curvature as 25 the concave surface 32.

It will be understood that when the metal plates 25 are bent upwardly there will be a frictional sliding action of one plate relative to the other for absorbing the rolling or 30 rocking action and any blow incident thereto, and that the absorption of such blow will be gradual to soften the blow to the greater extent.

With this three-piece bolster construction 35 I propose using the side and center bearings between the car body and equalizing bolster unit on the truck bolster for swivel action only, and as mentioned above, reduce the clearance between the side bearing members 40 11 and 12 to the least possible amount, in fact to a negligible amount, to insure concentration of the load on the center plates. In this way and also by reason of the three-piece bolster construction, the rocking force 45 is lowered, and the resultant load from this force is delivered nearer the center of the truck with the result that the consequent tendency of the wheel on the opposite side to lift is greatly reduced.

50 The provision for rocking of the equalizing bolster unit on the cross bolsters 20 at the center, by reason of the rounded bearing surfaces 18 on the equalizing bolster unit and the flat surfaces 19 on the cross bolsters 55 20, also the clearance between the equalizing bolster unit and the transverse bolster members 20 prevents side rocking between the center plates 14 and relieves, in a measure, the weaving of the car, the ends 21 of cross 60 bolster members 20 being free to follow elevations or depressions in the track.

It will also be observed that on account of the increase in distance from the side bearings 33 as distinguished from the side bearings 11 and 12 to the bearing points 21 at the

ends of the cross bolster, that the vertical movement of the ends of the cross bolsters 20 is proportionately greater than at the bearings 33, which adds greatly to the flexibility of the truck and the means for adjusting itself to imperfections of the track without affecting the car body. 70

By means of the arrangement herein shown and described, the objects of this invention are accomplished in a simple and efficient manner. 75

It is my intention to cover all modifications of the invention falling within the spirit and scope of the following claims. 80

I claim:

1. In a railway car, the combination of an equalizing bolster unit, a transverse bolster member upon which said bolster unit is rockably mounted, and shock absorbing means interposed between said equalizing bolster unit and said transverse bolster member for checking rocking movement of the car body. 85

2. In a railway car, the combination of a plurality of relatively movable bolster members, one being rockably mounted on the other, and shock absorbing means interposed between said bolster members for checking rocking movement of the car body. 90

3. In a railway car, the combination of a car body having side bearings, a bolster member having side bearings with substantially no clearance and cooperating with said body side bearings, another bolster member upon which the first bolster member is rockably mounted, and shock absorbing means interposed between said bolster members for checking the rocking movement of said car body on the truck. 95

4. In a railway car, the combination of a car body having side bearings, a bolster member having side bearings cooperating with the body side bearings, there being substantially no clearance between said side bearings, said bolster member having a center plate upon which the car body is adapted to swivel and being located at a point below said side bearings, another bolster member having side bearings cooperating with side bearings of the first bolster member, there being a clearance between said bearing members on said bolster members, the cooperating bearing members on said bolster members being substantially in the same horizontal plane with said center plate 100

110 for decreasing shocks occasioned by rocking of the car body, and shock absorbing means interposed between said bolster members for checking the rocking movement of said car body. 120

5. In a railway car, the combination of a car body having side bearings, a bolster member having side bearings cooperating with the side bearings of said body and having substantially no clearance therebetween, 130

said bolster having a center plate upon which said car body is adapted to swivel, and another bolster member having side bearings adapted to cooperate with side 5 bearings of the first mentioned bolster member and located inwardly with respect to the side bearings on the car body for reducing the rocking movement of said car body.

6. In a railway car, the combination of a 10 car body having side bearings, a bolster member having side bearings cooperating with the side bearings of said body and having substantially no clearance therebetween, said bolster having a center plate 15 upon which said car body is adapted to swivel, another bolster member having side bearings adapted to cooperate with side bearings of the first mentioned bolster member and located inwardly with respect to the 20 side bearings on the car body for reducing the rocking movement of said car body, and shock absorbing means interposed between said bolster members for checking the rocking movement of said car body.
- 25 7. In a railway car, a truck bolster including, in combination, two cross bolster members, an equalizing bolster member, girder members bearing normally on the middle of said cross bolster members and having a

limited amount of rocking movement with 30 respect thereto to insure equalization of the load to the ends of said cross bolster members, and shock absorbing means interposed between said equalizing bolster member and said cross bolster members for checking the 35 rocking movement of the car body on the truck.

8. In a railway car truck, the combination of a bolster member having a pocket, 40 spring metal plates arranged in a pile mounted in said pocket, and another bolster member having a bearing portion which, under certain predetermined conditions causes a compression of said pile of plates for absorbing shocks and checking the 45 rocking movement of a car body on the car truck.

9. In a railway car truck, a bolster member having a pocket, spring friction plates arranged in a pile within said pocket, and a 50 pile retaining member having a concave face associated with said pile whereby upon a compression thereof the plates are caused to bulge and have frictional movement one with respect to the other for absorbing shocks. 55

Signed at Chicago, Illinois, this 6th day of July, 1922.

JOHN A. LAMONT.
